UNITED STATES PATENT OFFICE.

EDGAR F. HATHAWAY, OF WELLESLEY, MASSACHUSETTS, ASSIGNOR TO SHAWMUT ENGINEERING COMPANY, OF DORCHESTER, MASSACHUSETTS, A CORPORATION OF MASSACHUSETTS.

GRINDING MECHANISM FOR THE SHEAR BLADES OF TUFT-FABRIC LOOMS.

Application filed May 1, 1922. Serial No. 557,799.

To all whom it may concern:

Be it known that I, EDGAR F. HATHAWAY, a citizen of the United States, and a resident of Wellesley, in the county of Norfolk and State of Massachusetts, have invented an Improvement in Grinding Mechanism for the Shear Blades of Tuft-Fabric Looms, of which the following description, in connection with the accompanying drawings, is a specification, like characters on the drawings representing like parts.

This invention relates to grinding mechanism and particularly to grinding mechanism for the shear blades of tuft fabric looms, and more especially to such mechanism so constructed and operated as to effect the grinding operation without removing the shear blades from the loom.

In order that the principle of the invention may be readily understood, I have disclosed a single embodiment thereof in the accompanying drawings, wherein—

Fig. 1 is an end elevation of the selected embodiment of my invention (with parts of the loom in section) as applied for grinding the swinging knife;

Fig. 2 is a transverse section through the grinding shaft, the grinding wheel being shown as acting on the sliding knife;

Fig. 3 is a detail in section of one form of means for locking the shift rod that controls the movement of the grinding device between the knives;

Fig. 4 is a front elevation of the disclosed embodiment of my invention, the sliding knife having been removed and the grinding wheel being represented as operating upon the swinging knife.

Fig. 5 is a plan view with parts broken away of the mechanism of the grinding mechanism in position upon the loom;

Fig. 6 is a view similar to Fig. 1 but representing the mechanism as applied to knives wider spread than those shown in Fig. 1; and

Fig. 7 is a side elevation representing the grinding mechanism as driven from an outside source of power.

The knives of pile fabric looms, such, for example, as the two knives extending transversely of a moquette loom for severing the ends of the tuft yarns, require frequent grinding. So far as I am aware, it has always been necessary to remove the knives

from the loom to grind them and then to replace them in the loom. This requires a number of hours during which time the loom is, of course, idle. In accordance with my invention, I have provided a grinding mechanism which may be applied to the loom and will grind the knives while in place in the loom. An important object of my invention, therefore, is to provide mechanism by means of which the knives of a textile machine, and particularly of a moquette or pile fabric loom may be ground while in place in the loom. Desirably and in the disclosed embodiment of the invention, the grinding means is mounted upon a carriage or movable support or frame, which is desirably supported on and guided by the knives themselves, though it may be supported upon the supports for the knives or upon some other suitable part of the loom. Desirably and in accordance with the disclosed embodiment of the invention the carriage is operated by a motor upon the carriage or upon some other support, and if desired and as herein shown the travel of the grinding mechanism may be automatically controlled, being desirably automatically reversed in its direction of travel at each side of the loom, the to and fro movement continuing until the grinding is effected.

I have herein disclosed the preferred embodiment of the invention and will describe the same without limiting myself thereto, inasmuch as I believe myself to be the first to grind or sharpen the blade or blades of a pile fabric or other loom without removing said blade or blades from their position in the loom.

Referring more particularly to Figs. 1 to 5, the framing of the loom is indicated at 1 in Fig. 2, and also in Figs. 4 and 5. It may be of any suitable type, construction or shape, and it is provided with supporting bars 2, 3, as shown in Figs. 1 and 2 for the two knives 4, 5. The path of the yarn is indicated in dotted lines in Figs. 1, 2 and 6 at 6, 7 and 8. The knives 4, 5 are of the usual or any desired type, since my invention pertains to means for grinding or sharpening the knives. Nevertheless the knives enter into the combination of mechanism embodying my invention in certain aspects of the invention, since desirably the

knife or knives constitute a support for the grinding mechanism. An example of a tuft pile fabric or moquette loom with which my invention is particularly adapted to be employed and also of the type of knife commonly used upon such a loom is shown in the patent to Hughes 1,363,790 dated December 28, 1920; in the drawings of said patent a swinging knife is indicated at 34 and a sliding and curved-edge knife at 57. In Fig. 2, the grinding wheel is represented as acting upon the knife 4 termed the sliding knife, the knife 5 being termed the swinging knife, and in Fig. 4 the grinding wheel is represented as operating upon the swinging knife. The knives 4, 5 are positioned transversely of the loom, extending from side to side thereof, and their function is to sever the ends of the tuft yarns that have been inserted in the shed, so that the ends of the said tuft yarns may be even throughout the entire width of the fabric. The constant operation of the knives for this purpose rapidly dulls them, as has been already stated.

In order to grind the knife or knives while in position in the loom, I desirably provide a movable support or frame for the grinder or grinding means, the same being shown in the disclosed embodiment of the invention as a traveling carriage, and for this purpose I have in the several figures represented a traveling carriage at 9, it extending transversely of the loom from side to side thereof and having mounted thereon the grinding head 11, shown most clearly in Figs. 1 and 2. The said grinding head is herein shown as driven by spiral gears 12, 13, also shown most clearly in said figures, the gear 13 being fast upon a shaft 14, which is mounted in a bearing 15, shown most clearly in Fig. 4 as secured to the grinding head 11. The said shaft 14 is extended and is coupled at 16 (see Fig. 4) to the shaft or spindle 17 of an electric or other motor 18 which in this embodiment of the invention is mounted upon the carriage 9, so as to reciprocate therewith. Therefore in this disclosure of my invention the entire mechanism may be termed self-contained.

The grinding head 11 is preferably mounted for adjustment in a segmental bearing 19 formed upon one face of the carriage 9, the centre from which the arc face of said segmental bearings is struck being the axis of the shaft 14.

Any suitable means may be provided to support the head 11 in adjustable position, so as to act upon the knife that is to be ground. Herein for the purpose I have represented the head 11 as having flanges 20 at opposite edges which are slotted and through which members 21 rigid with the carriage 9 protrude. Any suitable means, as, for example, cams 22, indicated in Fig.

4, which are swiveled upon the members 21 may be employed to secure the grinding head 11 in adjustable position rigidly with respect to the carriage 9, and so that the grinding wheel may bear against the knife 70 to be ground.

The grinding wheel is indicated most clearly at 23 in Fig. 2. It is fast upon a shaft 24 carried for rotation in suitable bearings in the grinding head 11 and the said shaft is double ended as indicated in Fig. 2, in order that another grinding wheel may be positioned thereon when the mechanism is to be used for grinding the knife 5. In other words the shaft 24 is adapted to receive a grinding wheel or member at each end to act upon the knife positioned nearest such end of the said shaft.

Any suitable means may be employed to drive the shaft 24. Herein for the purpose I employ the spiral gears already described and connections therefrom to a source of power which may be borne upon the carriage or may be extraneously supported. The spindle or shaft 14 is further provided with a worm 25 indicated in dotted lines in Fig. 1 and meshing with the worm wheel 26 fast upon one end of a shaft 27, the said shaft having a bearing 28 which is supported by the bridge bar 29 shown most clearly 90 in Fig. 4.

Secured upon the opposite end of the shaft 27 is a beveled gear 30 which engages oppositely positioned beveled gears 31 and 32 represented most clearly in Fig. 5. The said beveled gears 31, 32 are provided with extended hubs which are journaled in bearings 33, 34 shown in Fig. 5, the flanges 35 serving to prevent endwise movement of the said beveled gears 31, 32. The hubs of the said beveled gears 31, 32 are formed as sleeves in which is mounted for endwise movement a shaft 36 shown in Figs. 1, 2 and 5. The said shaft 36 has a beveled gear 38 110 fast on one end thereof.

Slidably mounted upon the said shaft 36 is a collar 39 provided at each end with clutch teeth 40 adapted to engage corresponding teeth formed upon the beveled gears 31, 32.

The clutch collar 39, although slidably mounted upon the shaft 36, is compelled to rotate therewith by reason of a key or spline, and therefore rotates with the gear 38, the direction of rotation of which latter gear is controlled according to the engagement of the said clutch collar 39 with one or the other of the said beveled gears 31, 32. Desirably I provide for automatic reversal of the direction of rotation of the said beveled gear 38; and for this purpose any suitable means may be provided. In the disclosed embodiment of the invention I have represented a fork 41 shown most clearly in Fig. 2 as engaging a recess formed in the periph- 130

ery of the clutch collar 39. As represented in Fig. 2, the said clutch collar is extended upward and through such extension passes a shift rod 42 shown also in Fig. 5, the said shift rod being rigid with the fork 41 and having bearings 43, 44, wherein it is mounted for longitudinal sliding movement. The said shift rod 42 has terminal portions or extensions 45, 46, which are adapted to engage abutments secured to the loom near the ends thereof. One of said abutments is indicated at 47 at the left in Fig. 5, and the other abutment is oppositely positioned so as to be engaged by the extension or end 46.

When the clutch collar 39 is shifted to engage one or the other of the beveled gears 31, 32, the shift rod 45 may be forcibly held in its position to which it has been moved by engagement with either end abutment 47, so as to prevent disengagement of the clutch collar 39 from that beveled gear with which it has become engaged. For this purpose any suitable means may be provided. In Fig. 3, I have represented one means for accomplishing this end.

One of the bearings, and herein the bearing 43, is provided with an extension 48, in which the said shift rod 42 is slidably supported. Notches 49, 50 are formed in the shift rod, and they are in turn adapted to be engaged by the pawl or tooth 51 longitudinally slideable in the extension 48, which thus forms a socket. The said tooth or pawl is yieldingly pressed against the shift rod 42 by the spring 52, a cap 53 forming an abutment for the spring as well as a guide for the stem 54 of the said pawl or tooth 51. Desirably I provide against rotation of the tooth or pawl 51 as by forming the stem thereof square in cross section, but any other means may be employed.

It will be evident that the tooth or pawl 51 yields whenever the end of the shift rod strikes one of the abutments 47, so as to permit the shifting of the rod 42 and the engagement of the tooth or pawl 51 with the other notch 49 or 50, as the case may be.

In order to effect the reciprocation or to and fro travel of the grinding head in the disclosed embodiment of the invention, the beveled gear 38 upon the shaft 36 meshes with a beveled gear 55 (see Fig. 5), which is fast upon one end of the shaft 56 (see Fig. 4), the said shaft being journaled in any suitable bearing 57 rigidly mounted in the bridge 29. Secured to the other end of the shaft 56 is a sprocket 58 shown most clearly in Fig. 4, which is adapted to engage a sprocket chain 59 extending transversely of the loom and secured at its ends by suitable supports, one of which is indicated at 60 extending from the loom frame 1. To provide for rigidity in the chain a suitable tightener 60 may

be provided. A guard 61, shown most clearly in Fig. 4, may be provided, it herein being shown as extending from the bearing 57 over the chain so as to ensure engagement of the sprocket 58 with the sprocket chain 59.

It will be evident that through the described gearing and cooperating parts, the carriage 9 will in the disclosed embodiment of the invention be moved lengthwise the 75 knife or knives and the direction will be reversed as the shift rod engages the respective abutments 47, so that the carriage constantly travels to and fro across the loom until the grinding of the blade upon which 80 the grinding head is operating is effected.

It is important that as the carriage 9 moves to and fro, the grinding wheel be suitably pressed against the knife that is being ground and that it be supported and guided in its travel. While for this purpose any suitable means may be provided, I have herein represented the following mechanism.

The carriage 9 is provided with supports 90 62, 63 shown most clearly in Fig. 5, and these supports are formed as at 64, 65, 66, 67 with bosses to which are swiveled arms 68, as indicated most clearly in Figs. 1 and 2. At the lower ends the said arms 68 are 95 provided with rolls 69, 70 which engage the faces, and the edges of the two knives 4, 5, which in the disclosed embodiment of the invention directly support and guide the grinding head. If desired, however, the 100 said mechanism may be otherwise supported and guided, as hereinbefore stated. The swiveled arms 68 are both pressed outwardly against the respective knives by suitable means, as, for example, by springs 71 which 105 are suitably coiled about the support for the arms and held at their ends as clearly indicated.

Usually the cutting edges of the knives 4, 5 are grooved in the direction of their 110 length to provide shear. In such case, it is important that suitably to guide the carriage 9 a yielding means of adjustment be provided, and any other support than that shown may be employed.

In order that the operating grinding wheel may be suitably pressed against the knife that is being ground, clamping nuts 72 (Fig. 4) are desirably provided by means of which the arms 68 carrying the guiding rolls 69, 70 may be clamped on the grinding side, and this will insure free action for the spring 71 to act on the arms 68 and the guide rolls bearing on the other knife which at such time is not being ground, the carriage 120 thus being pressed toward the knife to be ground and retaining a yielding pressure as the carriage travels to and fro.

The bosses 65, 66 above referred to are desirably provided with suitable projections 130

73 to support the bridge 29, and the several bearings, such as 28, 33, 34, 57 may be integral therewith or they may be secured thereto, suitable caps and fastenings being used therewith as may be required to permit ready assembling of the parts.

In certain cases, it may be necessary to grind the full length of the knife or knives, and in such case one set of guide rolls will 10 or may cease to function before the grinding wheel has completed its necessary travel. To provide for such contingency, attachments, such as are shown at 74 in Figs. 1 and 2, may be used to extend the guiding edges of 15 the knives, such attachment being herein shown for the knife 4, it being understood that a similar attachment may be employed for the knife 5.

In Fig. 6, a slightly modified form of my 20 invention is represented, it differing only in that there is a greater space between the knives herein indicated at 4', 5', which are shown in full lines, the knives 4, 5 being indicated in dotted lines. It will be noted 25 that the supports for the swinging arms 68 are so located that the same size grinding wheel may be used as in the narrow form shown in Fig. 1, and the angularity of the axis of the grinding shaft is adaptable to 30 both extremes by means of the segmental bearing of the grinding head, as will be clearly evident without further description.

I have stated that the grinding mechanism may be driven by a self-contained 35 motor or otherwise. In Fig. 7 I have represented a driving mechanism which is mounted apart from the carriage 9. Herein I have represented an electric motor 76, which is connected by a flexible shafting 77 with the 40 traveling carriage. The motor 76 is supported in any suitable manner, and for said motor may be substituted any other suitable source of or means for applying power.

It will be evident from the foregoing 45 description that the grinding mechanism is itself supported by the knife or knives to be ground, and the ground surface of the knife or knives acts as a guide for the successive grindings. This latter feature is of importance 50 because some knives or shears of pile fabric or like looms do not have a straight edge, but are either concave or convex on the edge, so that the shearing operation does not occur simultaneously across the 55 whole width of the fabric as shown for example in said patent to Hughes 1,363,790.

It will be evident that I have provided 60 for the automatic adjustment of the grinding wheel or element against the surface to be ground as well as in the disclosed embodiment of the invention for the automatic transverse of the grinding element to and fro across the loom or other machine carrying a blade or blades. Furthermore the grinding 65 wheel or element may be adjusted so that

any desired angle of shear can be properly ground.

Having thus described one illustrative embodiment of the invention, I desire it to be understood that although specific terms are employed, they are used in a generic and descriptive sense and not for purposes of limitation, the scope of the invention being set forth in the following claims:

1. An attachment for grinding the opposed knives of a moquette loom when in their open or spaced position upon the loom comprising in combination a carriage constructed and proportioned to be located between and supported by said knives for traversing movement across the loom between them, a shaft thereon, a rotary grinder upon said shaft and adapted to engage a knife to grind the same, guiding means upon the carriage continuously to effect grinding contact of said grinder with the knife to be ground, and mechanism for rotating said grinder during movement of the carriage. 75

2. An attachment for grinding the horizontally spaced shear blades of a moquette loom comprising in combination a carriage constructed and proportioned to be traversable along and between said spaced blades, said carriage having supporting and guiding means thereon, a grinding member upon said carriage and adapted to act upon a blade to grind the same, driving mechanism upon said carriage and cooperating means supported by the loom along the path of movement of said carriage, and means for operating said driving mechanism to effect the traverse of said carriage. 90

3. Mechanism for grinding the opposed cooperating knives for cutting the tuft yarns of a tuft pile fabric loom, said knives extending across the loom and in their open position having their cutting edges spaced a slight distance as compared with their length, comprising a carriage constructed and proportioned to be located between and supported by said knives for traversing movement across the loom in said space between them, a grinding member upon said carriage adapted to act upon the cutting edge of a knife, means for traversing said carriage, and guiding means effective during traverse of the carriage to hold said grinding member against the cutting edge of the knife to be ground. 105

4. An apparatus for grinding a knife of the opposed knives for cutting the tuft yarns of a tuft pile fabric loom, when said knives are in their open position upon the loom, comprising, in combination, a support or frame for the grinding member, said support or frame being constructed and proportioned to be moved longitudinally of and substantially between the vertical planes of the open knives, a grinding member upon said support or frame, adapted 110

to act upon the cutting edge of a knife of said opposed knives, means for effecting grinding movement of said grinding member, and means constituting a support and

5 guide for said support or frame during movement of the latter, for maintaining said grinding member in grinding relation to the knife to be ground.

10 6. An apparatus for grinding the opposed cutting edges of the cooperating shear blades of a moquette loom when in their open or spaced position upon the loom, comprising a traversable carriage constructed and proportioned to be located between and supported by said blades, a rotary grinding member supported by said carriage in operating position between said open blades with the grinding face of said member perpendicular to the edge of the blade to be ground, means for traversing said carriage longitudinally of and upon the shear blades, and guiding means to cause said grinding member to follow the contour of the blade edge to be ground.

15 7. An apparatus for grinding the opposed cutting edges of the cooperating shear blades of a moquette loom when in their open or spaced position upon the loom, comprising a carriage constructed and proportioned to be supported by and between said blades, a rotatable shaft upon said carriage and adjustably supported relatively thereto with its axis parallel to the plane of the blade to be ground, said shaft being adapted operatively to support a grinding member in position between the blades to grind the cutting edge of a blade, means for traversing said carriage longitudinally of and upon the shear blades, and guiding means to cause said grinding member to follow the contour of the blade edge to be ground.

20 8. An apparatus for grinding the substantially vertical cutting edges of the spaced shearing blades supported upon a moquette loom for relative movement in an approximately horizontal plane, comprising a carriage having means for supporting and guiding it for movement across the loom in the space between the open shearing blades, a grinding wheel upon said carriage, means to move the carriage, and means upon the carriage operative during movement thereof to press said grinding wheel against said vertical cutting edge of the blade to be ground.

25 9. Grinding mechanism for textile machinery having a pair of spaced knives comprising a movable carriage having a segmental bearing face, said carriage being constructed and proportioned to be located between and supported by said knives, a grinder head adjustable upon said face, a grinding wheel, a grinding shaft therefor carried by said grinder head, and means co-

operating with said wheel to maintain the latter in grinding relation to the knife to be ground.

30 10. Grinding mechanism for textile machinery having a pair of cooperating spaced knives comprising in combination, a grinder carriage constructed and proportioned to be supported by and between said knives, a rotatable grinder head supported thereon and having a grinder member, means to rotate said member, means carried by the carriage for traversing the latter along the knife or knives to be ground, guiding means upon the carriage, and means automatically to reverse the direction of movement of the carriage.

35 11. Grinding mechanism for textile machinery having a knife or knives comprising in combination, a frame having a sprocket chain extending along the path of movement of the grinding mechanism, a carriage having a sprocket gear engageable with and movable along said sprocket chain, a grinding member upon said carriage and adapted to act upon the knife or knives to be ground, and a motor for effecting the traverse of said carriage.

40 12. Grinding mechanism for textile machinery having a knife or knives comprising, in combination, a frame having a sprocket chain extending along the path of movement of the grinding mechanism, a carriage having a sprocket gear engageable with and movable along said sprocket chain, a grinding member upon said carriage and adapted to act upon the knife or knives to be ground, and a motor for effecting the traverse of said carriage, said motor being mounted upon the carriage.

45 13. Grinding mechanism for textile machinery having a knife or knives comprising in combination, a frame having a sprocket chain extending along the path of movement of the grinding mechanism, a carriage having a sprocket gear engageable with and movable along said sprocket chain, a grinding member upon said carriage and adapted to act upon the knife or knives to be ground, a motor for effecting the traverse of said carriage, said motor being mounted upon the carriage, and means to reverse the direction of movement of said carriage.

50 14. Grinding mechanism for textile machinery having a knife or knives comprising a traversable carriage, a grinding member mounted upon said carriage for grinding action, and one or more swiveled arms upon said carriage having grinding means adapted to engage the knife or knives to be ground.

55 15. Grinding mechanism for textile machinery having a knife or knives comprising a traversable carriage, a grinding member mounted upon said carriage for grind-

ing action, one or more swiveled arms upon said carriage having guiding means adapted to engage the knife or knives to be ground, and means to press said guiding means 5 against the knife or knives to be ground.

15. Grinding mechanism for textile machinery having a knife or knives comprising, in combination, a carriage, a shaft thereon, a grinder wheel upon said shaft and 10 adapted to engage a knife to be ground, a swiveled arm 68, and guide rolls carried by said swiveled arm and adapted to engage the knife in the movement of said carriage.

16. Grinding mechanism for textile machinery having a knife or knives comprising, in combination, a carriage, a shaft thereon, a grinder wheel upon said shaft and 15 adapted to engage a knife to be ground, a swiveled arm 68, guide rolls carried by said swiveled arm and adapted to engage a knife 20 in the movement of said carriage, and means automatically to traverse said carriage along the knife or knives to be ground.

17. Grinding mechanism for textile machinery having a knife or knives comprising, in combination, a carriage, a shaft thereon, a grinder wheel upon said shaft and 25 adapted to engage one of the knives to be ground, a pair of opposed arms 68 swiveled 30 upon said carriage and having rolls to engage opposed knives, thereby to guide the carriage end to press the grinder wheel against the knife that is being ground.

18. Grinding mechanism for textile machinery having a pair of opposed spaced 35 knives comprising a carriage constructed and proportioned to be located between and supported by said knives and having a grinding shaft, a grinding wheel thereon, 40 and means to traverse said carriage along and upon said knives and to reverse the direction of travel thereof including a clutch member, a pair of opposed gears having 45 clutch faces alternately to engage said clutch member, and means upon the carriage to guide it in its traversing movement.

19. Grinding mechanism for textile machinery having a pair of opposed knives comprising a carriage constructed and proportioned for movement along and between 50 said knives and having a segmental bearing, a grinder head adjustably supported upon said bearing, a shaft carried by said grinder head, means to rotate the shaft, said shaft being adapted to support a grinder disk upon either end for engagement with opposed knives to be ground, and yielding means to press the active grinder disk 55 against the knife first being ground.

60. 20. An apparatus for grinding the opposed knives for cutting the tuft yarns of a tuft pile fabric loom when in their open position upon the loom, comprising, in combination, a carriage constructed and proportioned for traversing movement longitudi- 65

dinally of and substantially between the vertical planes of the open knives, a rotary grinding member upon said carriage adapted to act upon the cutting edge of a knife, means for effecting rotation of said grinding member, and means for supporting and guiding said carriage during its traversing movement to maintain said grinding member in grinding relation to the knife to be ground. 70 75

21. An apparatus for grinding the opposed knives for cutting the tuft yarns of a tuft pile fabric loom when in their open position upon the loom, comprising in combination, a carriage having a rotary grinding member, said carriage being constructed and proportioned for traversing movement longitudinally of and with its said grinding member between the open knives in position to act upon a knife, means for effecting rotation of said grinding member and means for supporting and guiding said carriage during its traversing movement to maintain said grinding member in grinding 80 85 90 relation to the knife to be ground. 95

22. An apparatus for grinding a knife of the opposed knives for cutting the tuft yarns of a tuft pile fabric loom, when said knives are in their open position upon the loom, comprising, in combination, a support or frame for the grinding member, said support or frame being constructed and proportioned to be moved longitudinally of and substantially between the vertical planes of the open knives, a grinding member upon said support or frame, adapted to act upon the cutting edge of a knife of said opposed knives, means for effecting grinding movement of said grinding member, said support or frame being formed to be itself supported and guided at a side portion thereof upon a surface of the knife to be ground, while being moved therealong, whereby said grinding member may be maintained in its grinding relation to the knife to be ground. 100 105 110 115

23. An apparatus for grinding a knife of the opposed knives for cutting the tuft yarns of a tuft pile fabric loom, when said knives are in their open position upon the loom comprising, in combination, a support or frame for the grinding member, said support or frame being constructed and proportioned to be moved longitudinally of and with its grinding member between the said open knives in position to act upon a knife thereof, a rotary grinding member upon said support or frame adapted to act upon the cutting edge of a knife of said opposed knives, means to rotate said grinding member, said support or frame being formed to be itself supported and guided at a side portion thereof upon a surface of the knife to be ground, while being moved therealong, whereby said grinding 120 125 130 135

ing member may be maintained in its grinding relation to the knife to be ground.

24. An apparatus for grinding a knife of the opposed knives for cutting the tuft yarns of a tuft pile fabric loom; when said knives are in their open position upon the loom, comprising, in combination, a support or frame for the grinding member, said support or frame being constructed and proportioned to be moved longitudinally of and between said spaced blades, said support or

frame itself having a guiding formation thereon whereby it may at a side portion thereof be received upon and moved along an exposed surface of a knife whose edge is to be ground, a rotary grinding member upon said support or frame, and means to rotate said grinding member.

In testimony whereof, I have signed my name to this specification.

EDGAR F. HATHAWAY.
